UNITED STATES PATENT OFFICE.

WILBUR N. SQUIRES, OF JOPLIN, MISSOURI.

GEAR DRIVE.

Application filed November 29, 1922. Serial No. 803,972.

To all whom it may concern:

Be it known that I, WILBUR N. SQUIRES, a citizen of the United States, residing at Joplin, in the county of Jasper and State of Missouri, have invented certain new and useful Improvements in Gear Drives, of which the following is a specification, reference being had to the accompanying drawings.

This invention relates to improvements in deep well pumps and operating mechanisms therefor, and has for an important object the provision of a novel and improved reduction gearing for connecting power and pump pistons arranged at the base of a deep well whereby the length of stroke of the pump piston is decreased and the power thereof increased, and which is capable of insertion within the ordinary well casing.

A further object of the invention is to provide a compact and durable gear drive for connecting the pump and power pistons.

An additional object of the invention is to provide a reduction gearing connecting pump and power pistons of the character described and which are located within the casing of the well forming an improvement over that structure disclosed and set forth in my co-pending application for improvement in deep well pumps, filed November 13, 1922, Serial No. 600,598.

A still further object of the invention is to provide reduction gearing of this character in which the various parts are made in duplicate in so far as possible, thereby to permit construction of the gearing at a very low cost as compared with gearing of the ordinary type.

These and other objects I attain by the construction and arrangement shown in the accompanying drawings, wherein for the purpose of illustration is shown a preferred embodiment of my invention and wherein like reference characters designate like parts throughout.

In the drawings:—

Figure 1 is a vertical sectional view partially in elevation of a deep well pump constructed in accordance with my invention;

Figure 2 is an enlarged sectional view through the reduction gearing taken at right angles to the view shown in Figure 1;

Figure 3 is a section on the line 3—3 of Figure 1;

Figure 4 is a plan view of the castings employed;

Figure 5 is a vertical sectional view taken through the castings;

Figure 6 is a plan view of the lower section of the upper cross head;

Figure 7 is a plan view of the lower cross head; and

Figures 8 and 9 are sectional views of the three way valve employed.

Referring now more particularly to the drawings, the numeral 10 designates a retainer barrel, so termed since it is employed in retaining in assembled relation various parts of the apparatus to be hereinafter described. Disposed within the retainer barrel at the upper end thereof is a pump barrel 11 secured to the retainer barrel and having operating within its cylinder 12 a piston 13. The pump barrel 11, and more particularly the cylinder thereof, communicates with a discharge pipe 14. Secured within the lower end of the retainer barrel 10 is a fluid pressure motor 15 having operating therein a reciprocating piston 16 embodying a stem 17. The parts above described may be of any desired construction, but are preferably constructed in accordance with the structure set forth in my co-pending application above identified. Disposed within the retainer barrel 10 intermediate the motor 15 and pump barrel 11 is a reduction gearing 18 for connecting the pump and power pistons 13 and 16, and a control mechanism 19 controlling the supply of fluid pressure to the motor 15.

In the construction of the reduction gearing 18 I employ a pair of castings 20 exactly similar in construction and secured in the retainer barrel 10 in vertically spaced relation to one another. These castings 20 are in the form of a flat, thick disk of metal having formed in the upper face thereof a recess 21 slightly offset from the diametrical axis of the disk, designated by the line $a-a$, and adapted for the reception of a shaft 22 which is retained in position within the recess by means of bearing caps 23. This shaft has secured thereto a gear 24 having a predetermined number of teeth and is provided centrally with teeth 25 cut therein and having a predetermined reduction relation to the teeth of the gear 24. The casing is, of course,

2

provided with a recess in which the gear 24 seats. Formed through the casting at diametrically opposed points are openings 26, one of which communicates with the gear 5 recess and exposes the teeth of the gear for engagement and the other of which forms a guide. The casting has another pair of openings 27 formed therein which are likewise diametrically opposed and similarly 10 positioned, one of these openings 27 communicating with the recess 21 and affording access to the teeth 25 cut in the shaft 22 and the other of these openings 27 acting as a 15 guide.

15 In placing the castings 20 in the retainer barrel 10, one casting is rotated about its vertical axis through 180° with relation to the other casting. By this rotation, the opening 26 forming a guide in each of the 20 castings is aligned with the opening 26 of the other casting, affording access to the teeth of the gear 24. Similarly the opening 27 forming a guide in each of the castings is aligned with the opening 27 affording 25 access to the teeth 25 of the shaft 22, these openings being in each case vertically aligned.

To the piston rod 17 at its upper end is secured a cross head 28 guided by guides 29 30 secured to the walls of the retainer barrel 10. To the lower end of the piston rod 30 of the pump piston is secured a cross head 31 which operates in guides 32 carried by the wall of the retainer barrel. Depending from 35 the lower end of the cross head 31 at opposite sides thereof are racks 33 which extend through the openings 27 of the castings 20 and extending upwardly from the cross head 28 at opposite sides thereof are racks 40 34 which extend through the openings 26 of the castings 20. It will be seen that one of the racks 33 will extend through the guide opening 27 of the upper casting and in the lower casting in passing through its opening 27 will engage with the teeth of the shaft 22 thereof, while the other of the racks 33 in passing through the upper casting will engage with the teeth of the shaft 22 of the upper casting and will operate in the guide 45 opening 27 of the lower casting. Of the 50 racks 34, one in passing upwardly through the lower casting 20 will pass through the guide opening 26 thereof and in passing through the upper casting will engage with the gear 24, while the other of the racks 34 will engage the gear 24 of the lower casting 20 and pass through the guide opening 26 of the upper casting. In other words, at each of the castings the shaft is positively 55 driven by one rack 34 and positively drives a rack 33 so that the drive is supported by not a single rack but by a pair of racks.

The necessity for this construction will be obvious when it is considered that in 60 many instances it is necessary in deep wells to lift the oil for a height of 3000 feet, thus creating a tremendous head pressure. It is practically impossible to transmit to the base of a well of this depth a fluid pressure sufficient to operate a motor directly to overcome this head pressure. Furthermore, for the best pumping operation it is necessary that a steady slow stroke be applied to the pump piston and it is preferred that this stroke be not too long, since the long stroke 70 type of pump has a tendency to leakage, increasing as the length of the barrel increases. It is further necessary to provide suitable control mechanism for the motor 15, and this I provide by forming the cross head 80 31 of the pump piston of two spaced elements 35 and 36, held spaced by rods 36a, these elements being spaced apart a vertical distance sufficiently greater than the length of travel of the pump piston to permit insertion of 85 the mechanism hereinafter described.

The numeral 37 designates a fluid pressure feed pipe preferably connected with a source of compressed air, not herein shown, and which enters the pump barrel 11 90 through the upper end thereof. Within the retainer barrel adjacent the upper end thereof the pipe 37 is branched to form sections 38 and 39, each of which is connected by a three way valve 40 with the pipe communicating with one end of the cylinder of the motor 15. The three way valves 40 each comprise a casing 41 provided at its upper end with a pair of ports 42 and 43 and at its lower end with a single port 44 by means of 100 which it is connected with the pipe leading to the cylinder of the motor 15. Within the casing is a valve body 45 having a pair of ports 46 and 47 therein arranged at an angle to one another. These plates are so arranged that when the port 46 connects the port 42 of the body with the port 44 thereof, communication of the port 44 with the port 43 is cut off. Correspondingly, when the ports 44 and 43 are in communication, the 105 port 44 is closed for communication with the port 42. With the port 43 of each of these valves a discharge pipe 48 is connected, these discharge pipes being preferably connected and having the terminus thereof arranged at a considerable distance above the pump barrel 11. The valves 40 have the valve bodies 45 thereof arranged at right angles to one another so that when the port 46 of one of the valves is placing the ports 42 110 and 44 thereof in communication, the port 47 of the other of the valves is placing the ports 43 and 44 thereof in communication, one valve being exhausting as the other intakes. It will be seen that upon fluid pressure being admitted through the pipe 37, 115 pressure will be admitted to one end of the cylinder of the motor 15 and the other end of the cylinder of the motor will be in communication with the exhaust and accordingly the 120 125 130

piston 16 will be caused to shift. This shift through the reduction gearing hereinbefore described causes a motion of the cross head 31 and of the pump piston 13. The cross head 31 is provided with adjustable stop members 48 which co-operate with the stems 49 of the valves 40, each stop member embodying a pair of vertically spaced elements 50 which are adapted to alternately engage 5 the stem with which they coat. The elements 50 are preferably made adjustable so that the length of stroke may be varied as desired, this construction being fully set forth in the co-pending application above 10 identified.

In order to permit of passage of the pipes from the three way valves to the cylinder of the motor 15, I form in the casting 20 openings 51 and 52. The opening 51 opens 20 directly through the casting and will be connected with the similar opening of the other casting by a pipe or conduit 53 passing between the racks 33. The other of these 25 openings 52 is in the form of a channel having its outlet 54 diametrically spaced from its inlet so that upon reversal of the castings 20, the outlet of the upper casting is vertically aligned with the inlet of the lower casting, permitting connection thereof by a vertical 30 pipe 55.

From the foregoing it will be obvious that in accordance with my invention a compact and durable reduction gearing is provided which may be enclosed within a casing of 35 relatively small size, such as the casing of an oil well of considerable depth, and which may accordingly be employed for connecting a pump and the operating cylinder therefor located at the base of the well. It will furthermore be obvious that the construction as hereinbefore set forth is capable of many alterations and minor changes without materially departing from the spirit of my invention and I accordingly do not limit myself to the specific structure thereof except 40 as hereinafter claimed.

I claim:—

1. In a deep well pump, a retainer casing adapted for disposal at or adjacent the bottom of the well, pump and power cylinders arranged in opposite ends of said retainer casing and maintained in fixed relation thereby, pistons within said cylinders, and rack and gear reduction gearing connecting 50 said pistons and disposed within said retainer casing.

2. In a deep well pump, a retainer casing adapted for disposal at or adjacent the bottom of the well, pump and power cylinders arranged in opposite ends of said retainer casing and maintained in fixed relation thereby, pistons within said cylinders, rack and gear reduction gearing connecting said 60 pistons and disposed within said retainer casing, said reduction gearing including a

casting, a shaft rotatably mounted in said casting, a pinion and a gear carried by said shaft, a rack carried by the power piston and engaging the gear, and a rack carried by the pump piston and engaging the pinion. 70

3. In a deep well pump, a retainer casing adapted for disposal at or adjacent the bottom of the well, pump and power cylinders arranged in opposite ends of said retainer casing and maintained in fixed relation thereby, pistons within said cylinders, rack and gear reduction gearing connecting said pistons and disposed within said retainer casing, said reduction gearing including a casting, a shaft rotatably mounted in said 75 casting, a pinion and a gear carried by said shaft, a rack carried by the power piston and engaging the gear, and a rack carried by the pump piston and engaging the pinion, said casting having openings formed therein 80 forming guides for said racks.

4. In a deep well pump, a retainer casing adapted for disposal at or adjacent the bottom of the well, pump and power cylinders arranged in opposite ends of said retainer casing and maintained in fixed relation thereby, pistons within said cylinders, rack and gear reduction gearing connecting said pistons and disposed within said retainer casing, including a pair of spaced similar 90 castings arranged within the retainer casing and in reversed relation to one another, each casting being provided with a shaft bearing parallel but offset from its diametrical axis, shafts rotatably mounted in said bearings and each provided with a pinion and a gear, a pair of racks connected with each of said pistons, one rack of each of said pairs extending through the guide opening of the casting next adjacent the piston to which it 95 is attached and operatively engaging the shaft through the gear or pinion thereof at the other of the castings, the other rack of each pair operatively engaging the shaft of the first named casting and extending 100 through a guide opening formed in the second named casting.

5. In a deep well pump, a retainer casing adapted for disposal at or adjacent the bottom of the well, pump and power cylinders arranged in opposite ends of said retainer casing and maintained in fixed relation thereby, pistons within said cylinders, rack and gear reduction gearing connecting said 115 pistons and disposed within said retainer casing, including a pair of spaced similar castings arranged within the retainer casing and in reversed relation to one another, each casting being provided with a shaft bearing parallel but offset from its diametrical axis, shafts rotatably mounted in said bearings and each provided with a pinion and a gear, a pair of racks connected with each of said pistons, one rack of each of said pairs 120 extending through the guide opening of the 125 casting, said reduction gearing including a 130

casting next adjacent the piston to which it is attached and operatively engaging the shaft through the gear or pinion thereof at the other of the castings, the other rack of each pair operatively engaging the shaft of the first named casting and extending through a guide opening formed in the sec-

ond named casting, a source of fluid pressure for said motor, and conduits formed in said casting permitting passage of the fluid pressure to the motor.

In testimony whereof I hereunto affix my signature.

WILBUR N. SQUIRES.
